United States Patent Office

Des. 187,729
Patented Apr. 26, 1960

187,729

POULTRY SINGER

George Persak, Jr., Verona, N.J., assignor to Ann Beckstrand, Wildwood, N.J.

Application September 10, 1959, Serial No. 57,504

Term of patent 14 years

(Cl. D12—2)

Fig. 1 is a perspective view of a poultry singer showing my new design.

Fig. 2 is a front elevational view.

Fig. 3 is a bottom plan view.

I claim:

The ornamental design for a poultry singer, substantially as shown.
